BIRD FEEDER

Donald McDonald, Louisville, Ky.

Application November 19, 1958, Serial No. 53,446

Term of patent 3½ years

(Cl. D31—2)

Fig. 1 is a front elevational view of a bird feeder, showing my new design;

Fig. 2 is a right end elevational view thereof;

Fig. 3 is a rear elevational view thereof;

Fig. 4 is a top plan view thereof; and

Fig. 5 is a vertical section taken on lines 5—5 of Fig. 4.

I claim:

The ornamental design for a bird feeder, as shown.
